UNITED STATES PATENT OFFICE.

EARL C. HANSON, OF LOS ANGELES, CALIFORNIA, ASSIGNOR TO TITLE INSURANCE AND TRUST COMPANY, A CORPORATION OF CALIFORNIA.

WIRELESS PHONOGRAPH FOR HOSPITALS.

1,381,827.

Specification of Letters Patent. Patented June 14, 1921.

Application filed June 3, 1918. Serial No. 238,045.

To all whom it may concern:

Be it known that I, EARL C. HANSON, a citizen of the United States, residing at Los Angeles, in the county of Los Angeles and State of California, have invented a new and useful Wireless Phonograph for Hospitals, of which the following is a specification.

My invention relates to the art of reproducing sound, and more particularly to the art of reproducing music by use of a phonograph or the like.

The principal object of my invention is to provide a phonograph which may be used to transmit music to a plurality of persons who are out of the audible range of the phonograph proper.

My invention has a peculiar utility in connection with hospitals in which it is possible to install my apparatus in such a manner as to be entirely inaudible to all the patients except those provided with a receiving apparatus.

Referring to the drawings which are for illustrative purposes only—

Figure 1 is a diagram showing the method of assembling and connecting the sending apparatus to the phonograph.

Fig. 2 is a diagram of one form of a receiving apparatus.

Fig. 3 is a diagram of another form of a receiving apparatus.

Fig. 4 is a detail showing the method of mounting the transmitters on the phonograph, this detail being shown partly in section along a central plane.

Fig. 5 is a section on a plane indicated by the line 5—5 of Fig. 4, this plane being viewed in the direction of the arrows.

Fig. 6 is a diagram showing a modification of the apparatus necessary to adapt it to receive and transmit direct speech.

In the embodiment of my invention illustrated in these drawings, I utilize an ordinary phonograph which may be of the disk type, as shown, the record 11 being mounted on a table 12 turned by suitable means not shown. The reproducer 13 carrying the needle 14 is secured on the end of a tone arm 15, which in turn is loosely connected with a casting 16 mounted on the top of the phonograph 17. A continuous passage 18 forming a sound conduit is provided through the interior of the casting 16 and through the tone arm 15 to the re-

producer 13. The sound coming through this passage is led through four auxiliary passages 19 into four high efficiency telephone transmitters 20. Obviously a greater or lesser number of transmitters may be used if desired, the object of the plurality of transmitters being to provide a magnification of the sound.

I have found, however, that it is difficult, if not impossible, to work the transmitters in multiple by simply connecting them to common wires, and I have devised a method of overcoming this difficulty, as shown in Fig. 1.

In this figure I provide a transformer 30 having an iron core 31 and a single secondary 32. As many primaries 33 are provided as there are transmitters 20, each of the primaries being connected through a battery 34 with one terminal wire 35 of each of the transmitters 20, and the other terminal of each primary 33 being connected to a wire 36 forming the other terminal of all of the transmitters 20. The primaries 33 are desirably as nearly identical as it is possible to make them with respect to the number of turns and their relative magnetic position with relation to the core 31 and the secondary 32. The secondary 32 is connected at 37 to ground and through a wire 38 with an antenna 39.

In practice the apparatus just described is placed at any convenient location in or near the hospital, and the antenna 39 is run in close proximity to the building, as for example, around under the eaves or along the roof.

The method of operation of my invention is as follows:

A record 11 being placed on the table 12 and the phonograph being started, musical sounds travel through the passages 18 and 19 and vibrate the diaphragms of the transmitters 20 causing variable currents to flow through the primaries 33. These variable currents induce high tension audio frequency electro-static charges on the antenna 39, which in turn cause an electrostatic field which is transmitted through space in all directions, being, of course, most intense in the immediate neighborhood of the antenna 39. As this field is not audible or otherwise perceptible to human beings, it does not annoy or otherwise affect those patients in the hospital who do not desire or who are 110

- in no condition to hear music. In case it is desirable to allow a patient to hear the music, one or the other of the receiving sets shown in Fig. 2 or Fig. 3 may be used.
- 5 In Fig. 2, the patient's cot is shown at 50, this cot being provided with a mattress 51 which serves the purpose of an insulator, the cot 50 being grounded solidly. A high efficiency telephone receiver 52 is connected 10 through a condenser 53 directly to the cot 50, the other terminal of the receiver 52 being connected to a grip 54, which the patient desiring to hear the music grasps in his hand at the same time placing the receiver 52 at his ear. The electrostatic field produced by the sending apparatus above described is sufficiently strong to induce a potential between the body of the patient and the ground, the body of the patient acting 15 as one side of a condenser. Due to the variable charge produced by the variable strength of the field, the current will flow from the patient's body through the receiver 52 producing sounds therein which are 20 clearly audible to the patient, these sounds being the exact reproduction of the music played by the phonograph.
- In some cases it may be more convenient to use the apparatus shown in Fig. 3, in 30 which the cot 60 is mounted on insulators 61 and to which the receiver 62 is connected through a condenser 63 to the cot and through a wire 64 with the ground at 65. In this case both the patient and the cot 35 itself furnish the necessary capacity for collecting the electrostatic field, the current flowing from the cot through the receiver 62 and faithfully reproducing the original music.
- 40 In some cases I provide the apparatus shown in Fig. 6 in which a horn 70 is placed
- on the casting 16 into which speakers may talk. It is thus possible for the newspaper to be read into the horn 70, and for the various patients throughout the hospital who 45 desire to do so, to listen to the news, the remainder of the patients being entirely unaffected thereby.
- What I claim is:
1. A wireless phonograph for use in hospitals and the like comprising a transmitter of electrostatic energy and a receiving system comprising a bed, a mattress formed of suitable material to insulate a patient from the bed, a telephone receiver connected 55 at one terminal to ground and means connected to the other terminal of said receiver for making an electrical connection to the body of the patient.
  2. A wireless phonograph for use in hospitals and the like which comprises a transmitter of electrostatic energy and receiving means comprising a telephone receiver connected to a condenser and the other terminal of said receiver connected to a 60 metallic grip.
  3. A receiving system for electrostatic energy comprising a telephone receiver, a connection from said telephone receiver to a capacity means and another connection 70 from said telephone receiver to the human body whereby said body serves as a collector of electrostatic energy.
  4. A receiving system for electrostatic energy comprising a telephone receiver and 75 a circuit including said telephone receiver and the human body whereby said body serves as a collector of electrostatic energy.
- In testimony whereof, I have hereunto set my hand at Los Angeles, California, this 24th day of May, 1918.
- EARL C. HANSON.
